(57) **CLAIM**

The ornamental design for a display screen with animated graphical user interface, as shown and described.

DESCRIPTION

FIG. 1 is a front view of a display screen with an animated graphical user interface, showing a first image of the claimed design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The appearance of the graphical user interface sequentially transitions between the images shown in FIGS. 1-6. The process or period in which an image transitions to another image forms no part of the claimed design. The outermost broken line in each of the figures illustrates a display screen or portion thereof and forms no part of the claimed design. The remaining broken lines, illustrating portions of the graphical user interface, form no part of the claimed design.
